2,618,005

SCRAPING AND CLEANING IMPLEMENT

Clarence W. Harshbarger, Detroit, Mich.

Application June 5, 1951, Serial No. 229,927

6 Claims. (Cl. 15—236)

1

This invention relates to cleaning and scraping implements and particularly to an improved device for removing ice and other substances from surfaces such as the windshields of motor vehicles, sidewalks, roadways and the like.

An important object of this invention is to provide an improved efficient scraping and cleaning device for quickly and conveniently removing ice, hardened snow and other foreign substances from surfaces such as motor vehicles windshields, sidewalks, steps and roadways. Another important object of this invention is to provide an improved cleaning and scraping implement embodying parts designed in a novel manner for manufacture and assembly at low cost. Another important object of the invention is to provide a device of this character which is rugged and durable and which may have associated therewith certain novel features rendering the device usable for other cleaning operations. A further important object of the invention is to provide an ice scraper including novel cutting teeth having a limited universal movement so as to predispose their cutting edges in any direction in which the implement is used and which teeth are also permitted a limited angular movement relative to the implement. A still further important object of the invention is to provide a novel mounting for the teeth, which mounting is adapted to apply a point bearing contact on the teeth when the implement is pressed into engagement with a surface to be cleaned in order that the teeth may rotate and incline freely in use.

In carrying out the invention, one embodiment of the invention is of relatively small size adapted to be held in the hand of the operator and for such construction it is preferably composed entirely of plastic material. A plurality of teeth or pins are mounted in the body of the implement and arranged to project from the bottom side thereof. These pins are loosely mounted in the body for limited universal movement both rotationally and inclinably relative to the body and are provided with cutting edges on their projecting ends which are capable of adjusting themselves for the most efficient cutting action in whatever direction the body is moved. The maximum angular movement of the pins is controlled so as to provide the most efficient cutting action on ice or other coated surfaces.

The invention is capable of being exemplified in different forms and to incorporate certain features for cleaning and removing foreign substances other than ice from surfaces. Several modifications of the invention illustrated herein

2

embody elements for scraping and brushing away loose ice, snow and dust films on windshields and other surfaces. These additional elements are shown as associated in a single device having 5 teeth or pins for cutting and scraping solid layers of ice.

This invention constitutes an improvement to that described and claimed in my copending application for United States patent Serial No. 10 747,181, now Patent No. 2,556,691, dated June 12, 1951.

Various other objects, advantages and meritorious features will become more fully apparent from the following specification, appended 15 claims, and accompanying drawings wherein:

Fig. 1 is a bottom view of a device constructed in accordance with this invention and adapted to be held in the hand of an operator;

Fig. 2 is a vertical sectional view of the device 20 of Fig. 1 taken along line 2—2 thereof;

Fig. 3 is an enlarged detail vertical sectional view taken through a portion of the device of Figs. 1 and 2 and illustrating the manner in 25 which cutting teeth thereof are employed to scrape ice from an ice coated surface;

Fig. 4 is a perspective view of one of the cutting teeth or pins;

Fig. 5 is a top plane view of a modified form of the device and embodying cleaning features;

Fig. 6 is a side elevation of the device of Fig. 5;

Fig. 7 is a detail view of a modified portion of the device of Fig. 6 partly broken away in section;

Fig. 8 is a top plane view of another modification of the invention;

Fig. 9 is a side elevation of the device shown in Fig. 8;

Fig. 10 is a top plane view of a further modification of the invention, and

Fig. 11 is a side elevation of the working end 40 of the device illustrated in Fig. 10.

The various embodiments of the invention illustrated in the drawings are adapted to be held in the hand of the user and applied over an ice coated surface such as the windshield of a motor vehicle. For such use, it is preferred to make the devices substantially wholly out of plastic material. The invention, however, is applicable to larger scraping and cleaning implements such as for removing ice from roadways and sidewalks.

Referring to Figs. 1 to 4 inclusive, this particular embodiment of the invention comprises a body portion generally indicated at 10. This body portion is of a size and shape to be conveniently and firmly grasped in the palm of the

hand and for this purpose it is made non-circular in formation, being provided with a plurality of flat sides 12 forming a polygonal or octagon shape as shown in Fig. 1. For convenience in manufacture and assembly the body 10 is preferably composed of two superimposed plates or blocks 14 and 16 of plastic material. One plate, such as the plate 14, forms the upper portion of the body and as shown in Fig. 1 is preferably of the polygonal formation previously described. The upper surface of the top plate 14 is recessed as at 18 throughout substantially its entire area except for the margins thereof to form a depression for the purpose to be described hereinafter. The bottom plate member as shown in Fig. 1 is preferably of circular formation having a diameter slightly less than the transverse dimension of the upper member and centrally located thereagainst so that the flat sides 12 of the upper member project beyond the periphery of the lower member. In the final assembly the two members 14 and 16 are joined together and held against removal from one another.

The lower body portion 16 is shaped to form in combination with the upper member 14 an inner cavity or compartment occupying substantially the entire area of the portion except for the sidewalls thereof. This compartment as indicated at 20 in Figs. 2 and 3 and is completely enclosed except for the provision of the passages or apertures 22 in the bottom side 23 of the body portion 16. The passages 22 cover a large area of the bottom side of the body 10 and are preferably arranged in symmetrical order as shown in Fig. 1.

Mounted in the body 10 and projecting through the passages 22 are a plurality of ice cutting elements or teeth. These cutting elements correspond in size and shape to one another and are preferably composed entirely of plastic material or material less resistant than the surface upon which the device is to be used to remove ice and hardened snow. One such cutting element or tooth is illustrated in Fig. 4 and as shown therein is in the form of a stud or pin of plastic material having a shank portion 24 and head portion 26 on one end of the shank portion. The shank portion may be cylindrical in formation but is preferably rectangular or polygonal in cross section as shown in Fig. 4. At the juncture of the shank portion 24 to the head portion 26, each pin is preferably provided with a circular shoulder 28. Both the shoulder 28 and the shank portion 24 have a cross sectional dimension such that they are freely received within the passages 22 of the base portion 16 of the device. The relationship of the passage to the shank portions of the pins is such that the latter are capable of freely rotating in the passages and of inclining thereto in the manner illustrated in Fig. 3.

Each head 26 of the cutting element or pin is preferably cylindrical in formation as shown in Fig. 4 and the diameter of this head is constructed so that it is larger than the passage 22 through which the shank portion 24 extends. Thus, with the head 26 mounted within the compartment 20 of the body 10 and with the shank portion 24 extending through a passage 22, the pin is retained within the body against removal therefrom.

Each head 26 of the cutting element of the pin is further provided with a recess 30 opening out through the upper end of the head. The recess

30 is preferably conical in formation, reducing in lateral extent as the bottom is approached and terminating in a narrow base 32 which is slightly rounded as shown in Figs. 2 and 3. When mounted in the cavity or compartment of the body, the axial length of the heads 26 of the cutting pins is less than the height of the compartment as shown in Fig. 2.

The top plate portion 14 of the body 10 is provided, preferably at its time of manufacture, with a plurality of downwardly extending projections 34 corresponding in number to the number of pins and apertures in body and arranged in line with the axes of the passages 22. These projections 34 are each preferably of conical formations as shown in Figs. 2 and 3 reducing in lateral extent as they approach their lower extremities. The bottom ends of the projections 34 are preferably rounded and provided with a curvature corresponding approximately with that of the bases 32 of recesses 30. The length of the projections 34 are such that when the heads 26 rest on the bottom side 23 of the base plate 16 the terminating ends of the projections are spaced from the bases 32 of the recesses 30. However, when the device is applied to an ice coated surface, such as the glass windshield 36 shown in Fig. 3 and the pins are pressed against the ice coating 38 thereon, the pins are elevated in the compartment 20 bringing the terminating ends of the projections 34 into contact with the bases 32 of the recessed heads. In this manner a point bearing contact is formed between the projections and the heads, the former taking the axial thrust of the pins but at the same time freely permitting rotational and inclinable movement of the pins in the manner shown in Fig. 3. The conical sides of the recesses 30 and the projections 34 are so related that they govern the maximum inclination of the pins relative to the axes of the passages through which they extend. As shown in Fig. 2, the recesses 30 are made in oversize relation to the projections 34 and have their conical walls extending at a greater angle than the conical surfaces of the projections. At the maximum inclination of each pin, as shown in Fig. 3, the conical wall of the recess 30 of each pin facially abuts a side portion of the entering projection and is rigidly held by the latter from further tilting movement.

As a result of this construction, the pins are free to rotatably adjust themselves and to assume the desired inclination as the device is pressed against an ice coated surface and initially advanced in one direction thereover. The point contact provided between the ends of the projections 34 and the bases 32 of the recesses enables the pins in the initial movement of the device over an ice covered surface to rotatably adjust themselves so that they present one of the flat faces of the pin shanks perpendicular to the direction of sliding movement. The lower end of each shank thus presents a cutting edge transverse to the direction of movement and regardless of whether the movement is in straight or circular paths. The user therefore may apply circular or arcuate movements to the device as it is scraped over an icy surface and the pins will self adjust themselves to present a straight cutting edge extending substantially perpendicular to the direction of movement of the device at any given point of its travel.

After the ice on an ice coated surface has been loosened, the device may be inverted bringing its top portion into contact with the surface.

The flat sides of the upper body portion 14 may be used to scrape away the loosened sections and particles of ice from the surface.

Figs. 5 and 6 illustrate a modification of the device shown in Figs. 1 to 4 wherein certain additional operating elements are added thereto for performing other types of cleaning operations. Certain common features between the two devices are referred to by the same reference characters. The body of the modified device is composed of molded plastic material and is formed of an upper portion 14 and a lower portion 16 corresponding to these parts of the previously described embodiment of the invention. Similar cutting teeth or pins are provided for the modified device and are mounted in the hollow interior formed by the upper and lower portions of the body like that shown in Figs. 2 and 3. The shanks 24 of these pins are shown in Fig. 6 projecting from one side of the modified device.

The body portion 14 of the modification of Figs. 5 and 6 is provided with an outwardly projecting wall 40 of polygonal formation which may be of slightly reduced size as compared with the body portion 14 and project centrally therefrom in the manner shown in Fig. 5. The outer edge of the wall is beveled as at 42 to form an inwardly inclined cutting edge completely around the flat sides of the wall. This edge may be used in lieu of the scraping pins for removing frost and relatively easily dislodgable ice.

In addition, the modification of Figs. 4 and 6 is provided with a relatively long straight cutting edge for the removal of ice and other foreign matter from surfaces. For this purpose the body portion 14 is provided with a plastic extension 44 formed integrally therewith and projecting from one side thereof. The extension is relatively thin but extends for a considerable width of the device. Its outer end is beveled at 46 to provide a relatively long straight cutting edge. Projecting from the opposite side of the body is a similar but shorter extension 48 of plastic material which serves as a base support for a brush 50. The root ends of the bristles of the brush are embedded in the extension and project laterally therefrom. The incorporation of the brush in the device provides a convenient cleaning element for the user for removal of loose ice particles, snow and dirt.

The laterally projecting scraper element 44 may be modified as shown in Fig. 7 to provide a resilient tip in place of a plastic edge for wiping and scraping surfaces. As shown in Fig. 7, extension 52 corresponds to that shown at 44 and is provided with a recess which opens out through its outer edge. Received in the recess and projecting outwardly therefrom is a tapering body 54 of resilient material, such as rubber. This rubber-like material extends the full length of the extension and provides a yieldable edge for scraping and wiping loose material from surfaces such as automobile windshields.

The modification shown in Figs. 8 and 9 is generally similar to that previously described in connection with Figs. 5 and 6 except that in lieu of the brush 50 the device is provided with a handle 56. The body portion of the device is similar to that illustrated in the first embodiment of the invention of Figs. 1 to 4 inclusive and includes the upper portion 14, bottom portion 16, and the scraper pins 24. The upper body portion 14 is recessed as indicated at 18 providing a polygonally shaped wall therearound. The

side of the device opposite to the handle 56 is provided with an extension 58 similar in function to the extension 44 and having a beveled or tapered extremity 60 forming a relatively long straight cutting edge. The outer end of the handle may be provided with an aperture 62 for conveniently hanging the device from any suitable support. In use, the handle is grasped by the hand and pressure applied therethrough to move the device over the surface to be cleaned. The handle is held to apply the pins 24 to an ice covered surface. However, to remove loose ice and similar foreign matter, the device may be turned to present the cutting edge 60 for contact with the surface.

Figs. 10 and 11 show a further modification of the device illustrated in Figs. 8 and 9. Common parts of these two devices are indicated by the same reference characters. Provided in the recess 18 of the upper body portion 14 is a brush, the bristles of which are indicated at 64. The brush is located adjacent to the extension 58 and on the side of the device opposite to the pins 24. To form a suitable support for the bristles, the recess 18 is provided with an elevated area of plastic material 66 filling the end of the recess adjacent to the extension 58. As in the modification illustrated in Figs. 5 and 6, the root ends of the bristles are embedded in the plastic material of the rise or elevation 66.

What I claim is:

1. An ice scraper comprising, in combination, a body formed with a plurality of correspondingly shaped passages opening out of one side of the body, a plurality of correspondingly shaped pins, one for each passage of the body, said pins having shanks of less cross section than said passages and provided with a head on one end of a greater cross section than the passages, said pins having their heads mounted in the body with the shanks thereof extending through the passages and projecting beyond the side of the body out of which the passages open, said heads each being provided with a recess, and means forming part of the body projecting into the recess of each head and providing a point bearing contact with the base of the cavity when the projecting ends of the shanks are pressed against an ice covered surface.

2. An ice scraper comprising, in combination, a body having formed therein a plurality of correspondingly shaped parallel passages opening out of one side of body and opening inwardly into an enlarged compartment inside of the body, a plurality of correspondingly shaped pins each having a shank portion of greater length than the length of said passages and having a head on one end oversize the passages, said pins each being mounted in the body with its shank portion in a passage of the body and with the head thereof disposed in said compartment the clearance provided between the shank of each pin and the side walls of passage in which it is mounted permitting a limited inclination of the pin relative to the body, said heads of the pins each provided with an outwardly flaring recess, and a projection in the body for each pin entering said recess and adapted to engage the bottom of the recess with a point bearing contact.

3. An ice scraper comprising, in combination, a body having formed therein a plurality of correspondingly shaped parallel passages opening out on one side of the body and opening in the body into a larger cavity, a plurality of corre-

spondingly shaped pins each mounted in a passage of the body and provided with a rounded head disposed in the cavity of the body which is of a size to prevent withdrawal of the pin through the passage, said pins each projecting beyond the passages in which they are mounted and from said side of the body and being of a less cross section than the cross sectional area of the passages so as to provide a limited angular movement of the pin in any direction relative to the body, said heads of the pins each provided with a conical shaped recess opening from the side thereof opposite to the passages in which the pin is mounted, and a projection for each pin located in the cavity and forming a part of the body, said projections entering the recesses of said heads and adapted to engage the bottom of the recesses to exert an axial thrust on the pins when the projecting ends thereof engage an ice coated surface.

4. An ice scraping implement comprising, in combination, a hollowed body having a plurality of correspondingly shaped parallel passages opening at one end out on one side of the body and at the other end into the hollow interior of the body, a plurality of correspondingly shaped pins each having a shank portion and a relatively wide head on one end of the shank portion, said pins each being mounted in the body with the shank portion thereof extending through one of said passages and projecting beyond said side of the body and having the head thereof disposed in the hollow interior of the body to lock the pin within the body against withdrawal, the shank portion of each pin being substantially uniform in cross section throughout its length and being less in cross section than that of the passage sufficiently to provide a maximum angular movement of the pins in any direction relative to the body of approximately 12 degrees to the axis of its respective passage, said heads of the pins each provide with a conical shaped recess opening out from the side thereof opposite to the shank portion of the pin, and a conical shaped projection in the body for each pin entering said recess thereof and adapted to have its outer extremity engage the bottom of the recess to provide a point bearing contact therewith to take the thrust of the pin.

5. An ice remover comprising, in combination, a body of a size to fit within the palm of the hands with the fingers thereof engaging the sides of the body, said body provided with a plurality of passages each opening out through the underside of the body and terminating at the other end within the body in a cavity of greater cross sectional area than the passage, a pin in each

passage having a head portion of greater cross section than the passage disposed within the cavity for locking the pin against removal from the passage, the head of each pin provided with a conical shaped recess opening into the cavity on the side thereof opposite to the passage through which the pin extends, and a projection forming part of the body for each pin entering said recess and adapted to engage the bottom thereof to provide a point bearing contact for taking the thrust of the pin when the projecting end thereof is pressed against an ice coated surface.

6. An ice removing implement comprising, in combination, a body of a size to fit within the palm of a hand and having substantially parallel top and bottom surfaces, said body provided with a plurality of correspondingly shaped parallel passages each opening at one end out through the bottom surface of the body and terminating at the other end in an enlarged cavity within the body, a pin for each passage having a shank portion of greater length than the passage and a head portion oversize the passage, each pin being mounted in the body with the shank portion extending through the passage and projecting beyond the bottom side of the body and with the head portion disposed within the cavity so as to prevent withdrawal from the pin from the body, the shank portion of each pin being less in cross section than the passage in which it is mounted so as to provide clearance for limiting angular movement of the pin in any direction relative to the body, the head portion of each pin being provided with a conical shaped recess opening upwardly in the direction of the top surface of the body, and a downwardly depending projection in the cavity opposite each passage forming part of the body and entering the recess of the head portion of the pin in the passage opposite which it is disposed, said projections each having a length greater than the depth of conical recess in which it enters and adapted to engage the bottom of the recess to take the axial thrust of the pin when the projecting end of the shank portion is pressed against a surface.
